[57] CLAIM

The ornamental design for a table, as shown and described.

DESCRIPTION

FIG. 1 is a perspective view of a table showing my design;

FIG. 2 is a plan view from above;

FIG. 3 is a front view;

FIG. 4 is a lateral view from one side;

FIG. 5 is a lateral view from the other side.

The undisclosed rear surfaces of the table are plain and unornamented.
